Inventor:

Sisak K. Ouzoun-Boghosian

UNITED STATES PATENT OFFICE.

SISSAK K. OUZOUN-BOGHOSIAN, OF WASHINGTON, DISTRICT OF COLUMBIA.

WATCH-MOVEMENT CASE.

1,364,798.

Specification of Letters Patent.

Patented Jan. 4, 1921.

Application filed April 19, 1920. Serial No. 374,372.

To all whom it may concern:

Be it known that I, SISSAK K. OUZOUN-
BOGHOSIAN, a subject of the Sultan of Turkey,
having declared my intention of be-
coming a citizen of the United States, re-
siding at the city of Washington, District of
Columbia, have invented certain new and
useful Improvements in Watch-Movement
Cases, of which the following is a specifica-
tion.

This invention relates to improvements in
watch-movement-cases which are adapted
to fit and have secured therein a watch-
movement, in which case are provided means
to actuate the winding and setting mech-
anism of the watch movement, and there-
fore be used as a time-piece.

The object of this invention is to provide
a watch-movement-case which has the thick-
ness or depth, size and shape of a clock-
case, which watch-movement-case of the in-
vention is adapted to fit and have secured
therein a watch-movement, on which watch-
movement-case of the invention are provided
means to actuate the winding and setting
mechanism of the watch-movement, so that,
a watch-movement of the same size and de-
sired kind and quality can be readily fitted
and secured into the watch-movement-case
of the invention at any time desired, and
therefore it can be used as a desk-clock or
stand-clock.

The nature, characteristic features and
scope of the invention will be more fully
understood from the following description
taken in connection with the accompanying
drawings forming a part hereof and in
which:

Figure 1 is a perspective view of the
watch-movement-case of the invention.
Fig. 2 is a view in sectional side elevation
of the watch-movement-case of the inven-
tion, being sectioned at the dotted-line 2—2
in Fig. 1. Fig. 3 is a perspective view of
a modification of the watch-movement-case
of the invention, to which are fitted two
watch movements.

Similar reference characters refer to simi-
lar parts in all the figures of the drawings.
50 Referring specifically to the drawings, in
Fig. 1, the metallic tubular part 2 is af-
fixed to the top-plate 9, to which part 2 is
fitted the winding and setting crown 1.
The watch-case bezel 3 is removably fitted
55 onto the face-plate 5. A stem-wind watch-

movement 4 is fitted and secured into the
circular compartment 10 on the face-plate
5. Two posts 8, 8 are fixed on the top-plate
9, and the handle 7 is hinged to the posts 8,
8, thus forming a desk-clock or stand-
clock. The winding and setting mechanism
of the watch-movement 4 is actuated by the
crown 1.

In Fig. 2, the circular chamber 10 is
adapted to have fitted therein a watch-move-
ment of the same size. Flange 13 is adapted
to hold the watch movement from being
dropped into the case, and the two case-
screws of the watch-movement rest on the
circular flange 19, thus securing the watch-
movement in the circular watch-movement
chamber 10. The chambers 17, 11 and 18
are provided to render depth or thickness to
the watch-movement-case, and circular
chamber 11 is provided for the neatness in
appearance of the inside of the watch-move-
ment-case. The crystal 14 is fitted to the
bezel or rim 3, which bezel 3 is fitted to the
face plate 5. The back-cover 15 is fitted
over the circular opening 16. The circular
flange 13, circular chambers 10 and 11 and
the circular opening 16 communicate to-
gether. The stem-sleeve 20 being threaded
is secured into the tubular part 2. The
stem 21 is fitted into the sleeve 20, and the
crown 1 is secured to the stem 21. The
square part 22 of the stem 21 is adapted to
engage the winding and setting mechanism
of a stem-wind watch-movement, which
winding and setting mechanism of the
watch-movement is adapted to be actuated
by the crown 1 secured on the stem 21.

In Fig. 3, the watch-movement-case of the
invention is arranged to have fitted therein
two stem-wind watch-movements 4, 4, other-
wise, the arrangements and the construction
of the case are the same as in Figs. 1 and 2.

By the arrangement and construction of
parts described above and shown in the
drawings it will be evident that, the watch-
movement-case of the invention can be made
readily to have fitted therein any standard
size watch-movements, giving the privilege
of the use of any watch-movement desired,
as a desk-clock.

However, I do not limit myself to the
form of the watch-movement-case of the in-
vention shown in the drawings and de-
scribed herein, as it can be readily seen that
it can be made in many different forms and

styles and to fit the particular arrangements and requirements of different kinds of watch-movements, without departing from the principles of this invention.

5 Having thus described my invention what I desire to secure by Letters Patent of the United States and claim is:

1. A watch-movement-case adapted to have fitted and secured therewith a watch-movement and therefore to be used as a desk-clock, said watch-movement-case having means provided thereon to actuate the winding and setting mechanism of said watch-movement, having fitted a bezel with 10 a crystal on front-face of said case and a back-cover on back-face of said case, and being of the proportions of a small bracket clock-case.

2. A desk-clock-case adapted to have fitted 20 in a circular compartment at the front thereof a stem-wind watch-movement, said case having front and rear openings adapted to

be covered by a bezel with a crystal and a rear cover respectively, a winding stem sleeve and crown fitted in an opening at the 25 top of the movement compartment and adapted to engage with and operate the winding and setting mechanism of said watch-movement, said movement being secured in said case by the usual case-screws, 30 all substantially as set forth.

3. The combination of a desk-clock-case and a stem-wind watch-movement, said case having front and rear circular openings covered by the watch-bezel and back-cover 35 and a top opening through which extends a winding-stem, sleeve and crown, which stem engages with and operates the winding and setting mechanism of said watch-movement which is seated in a compartment in the case 40 and held therein by the usual case screws, all substantially as set forth.

In testimony whereof I affix my signature.
SISSAK K. GUZGUN-BOGROSSIAN.
